MINING MACHINE

Charles A. Pratt, Chicago, Ill., assignor to Goodman Manufacturing Company, Chicago, Ill., a corporation of Illinois

Application March 10, 1932, Serial No. 597,916
Renewed September 15, 1934

7 Claims. (Cl. 262—30)

This invention relates to improvements in mining machines of the room and pillar type and more particularly to coal mining machines slideable along the mine bottom while undercutting the coal.

This invention has among other objects to provide a new and improved mining machine of the class described adapted for use in thin seams of coal and constructed with a view towards ease and simplicity of operation, and ruggedness, compactness, and ready accessibility of parts including the motor.

The machine of my present invention is similar in many respects to that of my prior invention filed February 25, 1932, Serial No. 595,054, and entitled Improvements in mining machines, but differs from my prior invention in the arrangement of the feeding mechanism.

My invention may be more clearly understood with reference to the accompanying drawings wherein:

Figure 1 is a side elevation of a device embodying my invention mounted on a self-propelling truck;

Figure 2 is a top plan view of the device shown in Figure 1;

Figure 3 is a partial enlarged sectional view taken substantially along line 3—3 of Figure 2;

Figure 4 is a transverse sectional view taken substantially along line 4—4 of Figure 2; and

Figure 5 is a front end view of the device embodying my invention with parts broken away and in section to more clearly show the details thereof.

Like numerals refer to like parts throughout the various figures.

Referring now in particular to the details shown in the drawings, the embodiment of my invention illustrated comprises a vertically disposed motor 10 slideable on one of its ends on the mine bottom, and a main frame 11 carrying cutting and feeding mechanism extending forwardly of said motor.

A cutter bar 12 projects forwardly of the main frame 11 and is secured to a depending projection 13 extending forwardly and downwardly from said main frame by suitable nuts and bolts in a usual manner as may clearly be seen with reference to Figure 5. Said cutter bar is provided with a cutter chain 14 movable thereabout in a usual manner and driven from a cutter chain sprocket 15 freely mounted on the lower end of a vertical shaft 16. Said cutter chain sprocket and vertical shaft are driven from the motor 10

in a suitable manner which will hereinafter be more fully described.

Means are provided for moving the mining machine about the mine from working place to working place which may be of any suitable construction, but which means is herein preferably shown as being a track mounted truck 17. Said truck is driven from the mining machine motor 10, in a manner which will hereinafter be more fully described, for transporting the mining machine about the mine, and is provided with a pivoted forward end so said mining machine may readily be removed therefrom or loaded thereon in a usual manner well known to those skilled in the art.

The main frame 11 is attached to a casing 18 for the motor 10 by means of nuts and bolts indicated at 19 and forms a means for supporting the feeding and cutting mechanism and the drive means therefor. Said main frame is so arranged that a passageway is provided for discharging the cuttings to the retreating side of the machine, which passageway is closed to the advance and rearward sides thereof and conforms substantially to the path of the cutter chain 14 for discharging the cuttings to the retreating side of the machine in cooperation with said cutter chain. It should also be noted that the main frame 11 is so arranged that the portion adjacent the advance side of the mining machine rests directly on the mine bottom and serves as a support for the machine while the portion adjacent the cuttings passageway is raised to form a bottomless passageway for the discharge of the cuttings. This prevents clogging of the cuttings between the bottom and top portions of the cuttings passageway in that the cuttings not expelled from the cuttings passageway by the cutter chain 14 are left behind as the mining machine travels along the working face.

Referring now in particular to the motor 10 and motor casing 18, it may be seen with reference to Figure 1 that said motor casing is split diagonally into two halves, herein referred to as a forward half 20 and rearward half 21. The forward half 20 is bolted to the rearward end of the main frame 11 by means of the nuts and bolts 19 and the two halves are detachably secured together by means of suitable nuts and bolts in a usual manner. Said motor is of an ordinary construction having four wound field poles and being provided with a suitable armature (not shown) supported on a vertically extending armature shaft 24.

With reference to Figures 1 and 3, it may be

seen that the motor is so arranged that it is 5
slidable directly on the mine bottom adjacent an
end which is adjacent one end of the armature
shaft 24. It may also be seen that the armature
shaft 24 is supported in suitable bearings which
in turn are supported in bearing supports 26
and 27 adjacent its upper and lower ends, respec- 10
tively. The bearing supports 26 and 27 have a
grooved outer periphery which is adapted to be
engaged by suitable tongues formed in the for- 15
ward and rearward halves of the motor casing 18
so the armature and armature shaft 24 may be
readily removed therefrom with no vertical
movement thereof. It should be noted that due
to the fact that said motor casing is split diag- 20
onally, that its rearward half 21 may be re-
moved from the forward half 20 with a minimum
amount of rearward movement with respect to
the machine. With such an arrangement the
armature may be removed from the motor when 25
a breakdown occurs while the cutter bar is
sumped under the coal. Thus said motor is ar-
ranged so it may be readily accessible in confined
spaces and all parts of the motor may be re-
moved therefrom when the machine is at the 30
working face under varying conditions of min-
ing; as, for instance, where the space is very
limited as to length and height but where there
is ample width, which conditions are common in
mines, especially where the roof is poor and it is
necessary to space props for supporting the roof
close to the working face of the coal. 35
Referring now in particular to the drive for
the feed operating and cutter chain driving
mechanism, and several other novel features of
my invention, the upper end of the armature
shaft 24 has an armature pinion 29 keyed thereto. 40
Said armature pinion meshes with and drives
an idler gear 30 journaled on its hub in suitable
ball bearings supported in a bearing support 31.
Said idler gear is held in said bearing support
by means of a stud 32 integral therewith hav- 45
ing a nut threaded on its upper end. Said idler
gear meshes with and drives a spur gear 33 keyed
on the upper end of the vertical shaft 16 and
journaled on its hub in the bearing support 31
by means of suitable ball bearings of an ordinary 50
construction.
The bearing support 31 is of a T shape and is
supported adjacent the ends of the cross of the
T on suitable shoulders formed in the main
frame 11 on opposite sides thereof by means of
suitable cap screws in a usual manner. The stem 55
of the T extends rearwardly over the motor cas-
ing 18 and is provided with a suitable shoulder
which abuts and engages a projection extending
forwardly from the rearward portion of the main
frame 11 and is held to said projection by means
of suitable nuts and bolts in a usual manner. 60
With reference to Figures 2, 3, and 4, it may be
seen that upon removal of the bearing support
31 that the gears 30 and 33 may be removed from
the machine for accessibility to the cutter chain
drive and feed operating parts.
A worm 34 is cut integral with the vertical 65
shaft 16 and meshes with and drives a worm gear
35 keyed on a sleeve 36 freely mounted on a
longitudinally extending shaft 37 for driving the
feed operating mechanism for the mining ma-
chine in a manner which will hereinafter be
more fully described.
The cutter chain sprocket 15 is journaled on 70
its hub in the main frame 11 in suitable ball
bearings and is provided with a plurality of up-
wardly extending clutch jaws 38 adapted to be
75

engaged by clutch jaws 39 depending from a
clutch member 40 feathered on the vertical shaft
16 for selectively connecting said sprocket with
said shaft for driving the cutter chain 14 there-
from. 5

The clutch member 40 is moved along the ver- 10
tical shaft 16 by means of a suitable system of
levers which may be of any construction, but
which are herein preferably shown as comprising
a clutch yoke 41 having engagement with said 15
clutch member. Said clutch yoke is engaged by
a clutch fork 42 keyed on a transversely extend-
ing rock shaft 43 supported in the main frame
11 rearwardly of the vertical shaft 16 in suit-
able bearing supports in a usual manner. One 20
end of said transversely extending rock shaft
extends beyond the lateral boundaries of said
main frame adjacent the retreating side thereof
and has a hand lever 44 keyed thereto so move-
ment of said hand lever will vertically move the 25
clutch member 40 to engage the clutch jaws 39
with the clutch jaws 38 or disengage said clutch
jaws in an obvious manner. Suitable locking
means are provided to lock the clutch jaws 39
in an engaged position with or disengaged posi- 30
tion from the clutch jaws 38, which means com-
prises suitable pin and aperture locking means
generally indicated by reference character 45.

Referring now in particular to the feed mech- 35
anism and method of operating the same, a feed
drum 47 is keyed on a longitudinally extending
shaft 48 adjacent the forward end of the main
frame 11. The arrangement of said feed drum
is such that a flexible feeding member 49 may 40
be wound thereon and may readily be extended
to either side of the machine for moving the
machine along the mine bottom at either a high
or low speed in opposite directions without re-
versal of said motor. 45

The longitudinally extending shaft 48 is jour- 40
naled in suitable bearing supports formed inte-
gral with the main frame 11 and has a spur gear
50 keyed to its rearward end. Said spur gear
meshes with and is driven from a spur pinion
51 keyed on the longitudinally extending shaft 45
37 rearwardly of the bearing support for the
forward end of said shaft. 45

Suitable means are provided for driving the
longitudinally extending shaft 37 from the worm
gear 35 and sleeve 36 at the speed of rotation of 50
said sleeve or at a frictionally controlled lower
speed. Said means herein comprise a friction-
ally controlled eccentric gear reduction device
53 similar to that disclosed in my aforemen-
tioned prior application. Inasmuch as said ec-
centric gear reduction device has been fully dis-
closed in my aforementioned prior application it
will only herein be shown and described insofar
as is necessary to make the device of my present
invention readily understandable. Said friction-
ally controlled eccentric gear reduction device 55
comprises a casing 54 freely mounted on the lon-
gitudinally extending sleeve 36 for rotation with
respect thereto controlled by a friction band 55
engageable with the outer periphery thereof. 60
An eccentric 56 is formed integral with the
forward end of the sleeve 36 within the casing
54 and has a suitable ball bearing 57 thereon.
A gear 58 is mounted on said eccentric and
meshes with and drives an internal gear 59 jour- 65
naled within the casing 54 and supported on a
cage 60. A plurality of lugs 61 are formed inte-
gral with the gear 58 and have blocks 62 pivot-
ally supported thereon. Said blocks are slid-
able in suitable guides provided in the casing 55 70

75

in a manner similar to that described in my before mentioned prior application. When said casing is held from rotation by the friction band 55, rotation of the eccentric 56 will move the gear 58 in a non-rotatable closed orbital path for moving the internal gear 59 a distance equal to the width of the number of teeth in the gear 58 which engage corresponding teeth in said internal gear in a usual manner well known to those skilled in the art. The speed of rotation of the internal gear 59 is reduced by lessening the pressure of the friction band 55 on the casing 54 and allowing said casing to rotate within said friction band. Likewise, upon overload of the internal gear 59 the casing 54 will slip within the friction band 55 and prevent damage to the feed operating parts.

Suitable clutch means are provided for connecting the longitudinally extending shaft 37 with either the sleeve 36 for driving said shaft at the speed of rotation of said sleeve or the cage 60 for driving said shaft at the speed of rotation of the internal gear 59. Said means, as herein shown, comprise a clutch sleeve 63 having clutch jaws 64 on the rearward end thereof. Said clutch jaws are engageable with clutch jaws 65 formed integral with the sleeve 36 or clutch jaws 66 formed integral with the cage 60. The clutch sleeve 63 is shifted by means of a suitable system of levers in a usual manner which herein comprise a clutch fork 67 mounted on a transversely extending rock shaft 69 disposed beneath the longitudinally extending shaft 37 and having engagement with a suitable clutch yoke 70, which yoke is operatively connected with said clutch sleeve. Said rock shaft extends transversely of the main frame 11 beyond one side thereof, herein shown as being the retreating side of the mining machine, and has an operating lever 71 on its end adjacent the retreating side of the mining machine. It may thus be seen that the clutch sleeve 63 may be shifted along the longitudinally extending shaft 37 to cause said shaft to be driven at either a high speed or a low frictionally controlled speed.

The friction band 55 is engaged with or disengaged from the outer periphery of the casing 54 by means of a suitable system of levers in a usual manner operated from a hand wheel 73 on the rearward end of the machine.

Suitable means are provided to retard the rearward end of the mining machine as it is being fed across the coal face by the flexible feeding member 49 and feed drum 47, which may be of any suitable construction but which is herein shown as comprising a retarding drum 74 having a cable 75 wound thereon. Said retarding drum is freely mounted on a suitable stud extending rearwardly from the rearward end of the rearward half 21 of the motor casing 18 for free rotation with respect thereto.

Means are provided for retarding rotation of said retarding drum and controlling the paying off of the cable 75 therefrom, which means may be of any suitable construction but is herein preferably shown as being a brake band 77 adapted to engage said drum and operated by means of a suitable hand wheel 78 in a usual manner.

The flexible feeding member 49 may be trained directly from the feed drum 47 to a jack or any suitable holding means adjacent the face of the coal for feeding the machine therealong upon rotation of said feed drum. Said flexible feeding member may also be trained around a sheave 79 adjacent the forward advance side of the ma-

chine, over and under sheaves indicated at 80 on the advance side of the machine adjacent the central portion thereof, around a sheave 81 adjacent the rearward advance side of the machine, and around another sheave 82 adjacent the central rearward portion of the machine to a suitable connection on the truck for loading the machine onto said truck, as is clearly illustrated in Figure 2. Likewise, a sheave 83 is provided on the retreating rearward side of the machine for training the flexible feeding member 49 therearound. A guide roller 84 and sheave 85 are provided adjacent the forward retreating side of the machine for guiding the flexible feeding member for sumping or for moving the machine in a direction opposite its normal direction of travel.

Referring now in particular to the means for driving the truck 17 about the mine, a spur gear 86 is keyed on the hub of the spur gear 33 and meshes with and drives a spur gear 87 on the upper end of a vertically disposed shaft 88. A bevel pinion 89 is keyed on the lower end of said vertically disposed shaft and driven therefrom. Said bevel pinion meshes with and drives a bevel gear 90 journaled on its hub in the main frame 11 in a suitable manner. The outer end of the hub of the bevel gear is flush with said outer side of the main frame 11 and said hub is provided with a squared socket which is adapted to register with a squared shaft 91 slidably supported in a hub 93 of a drive sprocket 94 journaled in a bearing support member 95 extending upwardly and attached to the truck 17.

Suitable means are provided for locking the squared shaft 91 in engagement with the squared socket of the bevel gear 90 when the mining machine is supported on its truck and it is desired to move the mining machine on its truck about the mine, which locking means may be of any suitable construction but herein comprises a lever 96 pivotally supported on an extension from the bearing support member 95 and engaging the outer end of the squared shaft 91. Said lever is locked in an engaged position with said outer end of said squared shaft by means of a locking pin 97 indicated at 98.

Means are provided for operatively connecting the drive sprocket 94 with an axle 98 for the truck 17 and truck wheels 99 on said axle, which means comprises a chain and sprocket drive generally indicated by reference character 100. The forward and rearward truck wheels are in turn operatively connected together by means of a suitable chain and sprocket drive generally indicated by reference character 101.

Thus when the mining machine has been pulled onto the truck 17 by the flexible feeding member 49 and the squared shaft 91 is locked in an engaged position with the squared socket in the hub of the bevel gear 90, the truck may be driven from the mining machine motor 10 and the mining machine may be moved about the mine from working place to working place.

While I have herein shown and described one form in which my invention may be embodied, it will be understood that the construction and arrangement of the various parts may be altered or changed without departing from the spirit or scope of the invention. Furthermore, I do not wish to be construed as limiting myself to the specific embodiment illustrated, excepting as it may be limited in the appended claims.

I claim as my invention:

1. In a mining machine, a motor slidably directly on the mine bottom and having a vertical

- 5 having a cutter chain guided for movement thereabout, feeding mechanism therefor comprising a feed drum disposed adjacent the forward end of said main frame for rotation about a longitudinally extending axis and having a flexible feeding member adapted to be wound thereon, and means for selectively driving said feeding and cutting mechanism from said motor comprising a vertical shaft driven from said armature shaft and having a cutter chain drive sprocket freely mounted on its lower end, clutch means for selectively connecting said sprocket with said shaft, a shaft extending longitudinally of said main frame and journaled therein at its forward and rearward ends, means for selectively driving said longitudinal shaft from said vertical shaft at either a low speed or a higher frictionally controlled speed comprising a frictionally controlled geared speed reduction device coaxial with said longitudinal shaft and a geared connection between said feed drum and longitudinal shaft comprising a shaft coaxial with the axis of rotation of said drum and having its axis of rotation disposed adjacent the longitudinal center line of said cutter bar, an operative connection between said shaft and feed drum and a geared connection between the inner end of said shaft and said longitudinal shaft.
- 10 2. In a mining machine, a motor slidably directly on the mine bottom and having a vertical armature shaft, a frame disposed forwardly of said motor having a projecting cutter bar extending forwardly therefrom, said cutter bar being disposed in planes which intersect said motor and having a cutter chain guided for movement thereabout, feeding mechanism therefor comprising a feed drum disposed adjacent the forward end of said main frame for rotation about a longitudinally extending axis and having a flexible feeding member adapted to be wound thereon, and means for selectively driving said feeding and cutting mechanism from said motor comprising a vertical shaft driven from said armature shaft and having a cutter chain drive sprocket freely mounted on its lower end, clutch means for selectively connecting said sprocket with said shaft, a shaft extending longitudinally of said main frame and journaled therein at its forward and rearward ends, means for selectively driving said longitudinal shaft from said vertical shaft at either a low speed or a higher frictionally controlled speed comprising a frictionally controlled geared speed reduction device coaxial with said longitudinal shaft and a geared connection between said feed drum and longitudinal shaft comprising a shaft coaxial with the axis of rotation of said drum and having its axis of rotation disposed adjacent the longitudinal center line of said cutter bar, an operative connection between said shaft and feed drum and a geared connection between the inner end of said shaft and said longitudinal shaft.
- 15 3. In a mining machine, a motor slidably directly on the mine bottom and having a vertical armature shaft, a frame disposed forwardly of said motor having a projecting cutter bar extending forwardly therefrom, said cutter bar being disposed in planes which intersect said motor and having a cutter chain guided for movement thereabout, feeding mechanism therefor comprising a feed drum disposed adjacent the forward end of said main frame for rotation about a longitudinally extending axis and having a flexible feeding member adapted to be wound thereon, and means for selectively driving said feeding and cutting mechanism from said motor comprising a vertical shaft driven from said armature shaft and having a cutter chain drive sprocket freely mounted on its lower end, clutch means for selectively connecting said sprocket with said shaft, a shaft extending longitudinally of said main frame and journaled therein at its forward and rearward ends, means for selectively driving said longitudinal shaft from said vertical shaft at either a low speed or a higher frictionally controlled speed comprising a frictionally controlled geared speed reduction device coaxial with said longitudinal shaft and a geared connection between said feed drum and longitudinal shaft comprising a shaft coaxial with the axis of rotation of said drum and having its axis of rotation disposed adjacent the longitudinal center line of said cutter bar, an operative connection between said shaft and feed drum and a geared connection between the inner end of said shaft and said longitudinal shaft.
- 20 4. In a mining machine, a motor slidably directly on the mine bottom and having a vertical armature shaft, a frame disposed forwardly of said motor having a projecting cutter bar extending forwardly therefrom, said cutter bar being disposed in planes which intersect said motor and having a cutter chain guided for movement thereabout, feeding mechanism therefor comprising a feed drum disposed adjacent the forward end of said main frame for rotation about a longitudinally extending axis and having a flexible feeding member adapted to be wound thereon, and means for selectively driving said feeding and cutting mechanism from said motor comprising a vertical shaft disposed forwardly of the motor and driven therefrom and having a cutter chain drive sprocket freely mounted on its lower end, clutch means for operatively connecting said cutter chain drive sprocket with said vertical shaft, a worm on said shaft, a worm gear rotatable about an axis extending longitudinally of the machine driven by said worm, frictionally controlled gear reduction means driven by said worm gear, a shaft coaxial with said worm gear and journaled in said main frame adjacent its forward and rearward ends, clutch means for operatively connecting said shaft with said worm gear or said frictionally controlled gear reduction means and a geared connection between said feed drum and longitudinal shaft comprising a shaft coaxial with the axis of rotation of said drum and having its axis of rotation disposed adjacent the longitudinal center line of said cutter bar, an operative connection between said shaft and feed drum and a geared connection between the inner end of said shaft and said longitudinal shaft.
- 25 5. In a mining machine, a motor slidably directly on the mine bottom and having a vertical armature shaft, a main frame disposed forwardly of said motor having a projecting cutter bar extending forwardly therefrom, a cutter chain mov-

- <p

- able about said cutter bar, feeding mechanism therefor comprising a feed drum having a flexible feeding member wound thereon, means for driving said cutter chain and feeding mechanism 5 from said motor comprising an armature pinion on said armature shaft, an idler gear driven by said armature pinion, a spur gear driven by said idler gear, a shaft coaxial with and driven from said spur gear, means connectible with said shaft 10 for driving said cutter chain and feed drum, and means for supporting said idler gear and spur gear whereby said idler and spur gears may be removed as a unit to permit accessibility to said cutter chain and feed drive mechanism comprising 15 a T shaped bearing support member detachably secured to opposite sides of said main frame and extending rearwardly therefrom over and having engagement with the top portion of said motor.
- 20 6. In a mining machine, a motor slidable directly on the mine bottom having a vertical armature shaft, said motor having a motor casting split diagonally in a vertical plane the size of which determines the power producing functions 25 of the motor, a frame disposed forwardly of said motor having a projecting cutter bar extending forwardly therefrom, said cutter bar being disposed in planes which intersect said motor and having a cutter chain guided for movement thereabout, and means for feeding said mining machine along the mine bottom in opposite directions without reversal of the motor at either a high speed or a lower frictionally controlled speed comprising a vertical shaft driven by said 30 motor, a worm gear driven therefrom, a shaft extending longitudinally of said frame coaxial 35 with said worm gear journaled in said main frame adjacent its forward and rearward ends, a frictionally controlled geared reduction device coaxial with said longitudinal shaft and driven by said worm gear, clutch means for connecting said longitudinally extending shaft with either said frictionally controlled geared reduction device or said worm, a feed drum at the forward end of said main frame disposed substantially in alignment with the longitudinal center line of said cutter 10 bar, a shaft to which said feed drum is connected and a spur gear on the inner end of said shaft driven by said longitudinally extending shaft.
7. In a mining machine, a motor slidable directly on the mine bottom having a vertical armature shaft, a main frame disposed forwardly of said motor having a projecting cutter bar extending therefrom, a cutter chain movable about said cutter bar, means for driving said cutter chain from said motor comprising an armature 20 pinion on the upper end of said armature shaft, an idler gear meshing therewith, a vertical shaft, a sprocket meshing with said cutter chain on the lower end of said vertical shaft having selective connection therewith and a spur gear on the upper end of said vertical shaft driven by said idler gear, and means for supporting said idler and spur gears whereby said idler and spur gears may be removed as a unit to permit accessibility to said cutter chain and drive mechanism therefor 25 comprising a bearing support member extending across and detachably secured to opposite sides of said main frame and having a portion extending rearwardly therefrom over and having engagement with the top portion of said motor. 30

CHARLES A. PRATT.
